APPARATUS FOR ENCASING MAGNETIC CORES
Charles S. Mueller, Philadelphia, Pa., assignor to
Magnetic Metals Company, Camden, N.J.
Filed Apr. 13, 1964, Ser. No. 359,314
8 Claims. (Cl. 336—92)

This invention relates to apparatus for encasing magnetic cores in such a manner that damping materials of the kind heretofore used are not required.

Magnetic cores are well known in the art and are used particularly in magnetic amplifiers, saturable reactors and transformers, magnetic relays, etc. Commonly, such cores are of toroidal shape formed by winding thin strips of magnetic material of varying thickness into toroidal core form. The core may or may not have an air gap, nor is the present invention limited to cores having an annular configuration. The core is encased in a non-magnetic case which may be formed of thermoplastics, thermosetting plastics, or a non-magnetic metal such as aluminum. The general practice is to construct the core and its enclosure in such a way that there is clearance between the core and the walls of the casing, thereby permitting expansion and contraction of the core without binding the latter since it is important to avoid introducing strains on the cores because of the deterioration of magnetic characteristics which may then occur.

It has been the practice in the prior art that before or after the toroidal core of strip material is placed in its case, all the free space remaining between the core and its enclosure be filled with a damping material such as silicone rubber, fluid, grease, or oil, before finally sealing the casing. It has heretofore been considered essential that such damping material be used to avoid rattling of the core in its casing and to avoid strains on the core resulting from distortions of the casing since all such effects have been found to result in adverse effects upon the core's magnetic properties.

It will readily be appreciated by one skilled in the art that there are a number of problems associated with the use of a damping compound such as the silicone fluids, greases, rubber, or oils referred to previously. First of all, such compounds are quite expensive, and this in itself necessarily raises the cost of each core. Another factor is the increased labor costs in manufacturing cores resulting from the necessity of filling each casing with the damping medium after the core has been inserted. In addition, it frequently happens that some of the damping medium inadvertently gets onto the outside of the case, and then additional labor is involved in removing such material.

Described briefly, the present invention comprises an improved casing which makes it possible to dispose entirely of the use of damping compounds in the manufacture of magnetic cores. The improved casing of one embodiment of this invention includes, in part, a toroidal receptacle which forms a part of the casing and has a U-shaped radial cross-section to receive the core, but with the bottom surface thereof having a plurality of permanently deformable, resilient, or frangible upstanding elements which support the core upon its insertion and are permanently deformed upon the application of pressure by the core on such elements, whereupon a permanent deformation takes place having the exact configuration of the core bottom so as to prevent its lateral shift-

2

ing when the casing is sealed. Various constructions and modifications of the present invention are illustrated, including particularly one form in which both upper and lower portions of said casing have such upstanding deformable elements so that both have core-receiving cavities formed therein when the two portions are tightly brought together with the core in place. Incidentally, it is recognized that this results in the application of some stresses on the top and bottom surfaces of the core itself, but these are minimal because of the permanently deformable or frangible nature of the upstanding elements, and, furthermore, because the construction prevents the application of any stresses to the sides of the magnetic core.

Considered more generally, the present invention relates to an encased magnetic core which comprises an encasement for receiving the core with a clearance between the inner side wall of the encasement and the outer wall of the core, together with means for preventing vibration of the core within the encasement, this latter means comprising permanently deformable upstanding elements on at least the bottom wall of the encasement together with enclosure means for the encasement which is adapted to exert pressure on the core on its one surface so as to press its opposite surface against the deformable means, whereby a recess is formed in the deformable means that tightly holds the core in place and prevents lateral shifting and vibration within the encasement.

It is, accordingly, an object of this invention to provide encased magnetic cores to be construed that no damping fluids are required.

It is another object of this invention to provide an encasement for magnetic cores having frangible support means for the core in the bottom of the case which become permanently deformed when the core is placed in the case so as to hold the core immovably therein.

It is a further object of this invention to provide a plastic case of magnetic cores having upstanding frangible rib members in the bottom of at least one portion of the case which break away in part when a core is inserted therein and with pressure applied thereon, subsequent to which the core is relatively immovable laterally in said case.

Still another object of this invention is to provide a magnetic core comprising a case containing a so-called "spider" or washer-type element which can be inserted into the bottom of at least one portion of the case, with the spider having upstanding, frangible rib members for supporting the core when placed therein but with the upstanding rib members being frangible or permanently deformable so as to automatically form therein a cavity for receiving the core when the latter is placed with pressure on said spider, so that said spider will thereafter immovably hold said core in place within its encasement.

Other objects, purposes, and characteristic features of the invention will be in part obvious from the accompanying drawing and in part pointed out as the description of the invention progresses.

In describing this invention, reference will be made to the accompanying drawings in which:

FIGURE 1 is an exploded view showing a magnetic core of the present invention including its case, with the upper and lower portions thereof separated and also showing the toroidal magnetic core;

FIGURE 2 is a plan view of the upper half portion of the case.

FIGURE 3 is a cross-sectional view of a portion of the upper case portion of FIGURE 2 taken along the line 3—3 of FIGURE 2;

FIGURE 4 is a plan view of the lower half portion of the case shown in FIGURE 1;

FIGURE 5 is a cross-sectional view of the lower case portion of FIGURE 4 taken along the lines 5—5 of FIGURE 4;

FIGURE 6 is a cross-sectional view showing the upper and lower case portions in juxtaposition and with the inner magnetic core in place but with the two half case portions separated a slight amount;

FIGURE 6A is a view similar to that of FIGURE 6 but showing the two case portions brought tightly together under pressure;

FIGURE 7 is a cross-sectional view taken along the line 7—7 of FIGURE 4; and

FIGURES 8, 9 and 10 illustrate alternative embodiments of the present invention.

Referring to FIGURE 1, the exploded view shown there illustrates a bottom toroidal casing member 10 which may be formed of a thermosetting general purpose phenolic material, such as Bakelite, a tape-wound core 11 of magnetic material, and an upper casing member 12 which is generally similar to the member 10 and may also be formed of the same material as member 10. FIGURE 1 shows that the member 10 has on its inner bottom surface a plurality of integral upstanding ridges 13 which are generally radial in nature and are spaced at substantially equal intervals about the bottom of the inside surface 10a of the member 10 so as to provide a support for the magnetic tape-wound core 11 when it is inserted within the casing 10. When the members 10 and 12 are formed of a phenolic material as previously mentioned, it is then preferable that the member 12 also have the upstanding members or ribs on its inner surface in a manner analogous to that shown for the toroidal member 10. Such upstanding ribs are, of course, not evident in FIGURE 1 since it shows only the upper smooth surface of this particular member.

FIGURES 2 and 4 illustrate the fact that both these members 10 and 12 may have the integral upstanding ribs disposed substantially equidistantly and radially about their bottom inner surfaces; this FIGURE 2 shows the upper casing member 12 as having upstanding ridges 13a, and FIGURE 4 shows the lower casing member 10 with its similar upstanding ridges 13. Although six such ribs are shown in both FIGURES 2 and 4, it is evident that proper support for the tape-wound core member 11 shown in FIGURE 1 could also be provided by having as few as three such radial ribs. Of course, more than six such ribs can also be provided and such modification is also within the scope of this invention.

FIGURES 3 and 5, respectively, comprise cross-sectional views of the outer toroidal portions of the members 12 and 10. The ribs 13 and 13a are shown with respect to each of the members 10 and 12. FIGURE 7 is a cross-sectional view taken along the line 7—7 of FIGURE 4 and particularly illustrates in cross-section one of the upstanding ribs 13, showing it to be generally knife-edged so that the knife-edge can be broken away when the material is of a frangible nature such as the phenolic material mentioned previously, and when force is applied to the knife-edge by the core bottom. As illustrated in FIGURE 7, it has been found in practice that a rib constructed to have an angle of approximately 20° works very satisfactorily when the material used is a general purpose phenolic. If the rib has too great an angle, it is too stiff and will not readily break off at its top, knife-edged portion when pressure is exerted thereon by the bottom surface of magnetic core 11. On the other hand, if the angle is too small, the ridge breaks off too readily and may break off substantially entirely when pressure is exerted thereon by core 11 or may break off during tumbling of the plastic parts which is often resorted to when

the individual parts are made by compression molding. With respect to the height of the rib 13 above the bottom surface 19, it has been found that when a general purpose phenolic material is used, a height in the order of .02 of an inch is desirable. Of course, the dimensions given here are those which have been found to be satisfactory when the encasement is formed of a general purpose phenolic, but it will be understood that different dimensions may be required when other types of materials are employed.

FIGURES 3 and 5 also illustrate how the two portions 10 and 12 of the encasement may be constructed so that they tend to interlock when assembled. Thus, the depending circumferential shoulder 29 on member 12 is adapted to abut ledge 30 on member 10; similarly, the circumferential shoulder 27 on member 12 is adapted to abut ledge 28. In addition, shoulder 27 is provided with a slight rounded projection 15 on its inner side which is adapted to snap into a corresponding indentation 16 on ledge 28 when the members 10 and 12 are brought fully together. However, it has been found that successful encased magnetic cores can be made which do not employ the interlocking means thus illustrated but merely rely upon the close tolerances provided between the inner diameter at 17 on member 12 and the outer diameter at 18 on member 10 so that when the two halves of the encasement 10 and 12 are assembled, frictional forces hold them tightly together.

FIGURE 6 illustrates one step in the operation of assembling the complete core and FIGURE 6A illustrates the completion of the assembly operation. FIGURE 6 illustrates the fact that the parts 10 and 12 are so dimensioned, particularly with respect to the combined depths of their toroidal U-shaped portions relative to the height 35 of the core member 10 itself, that when the core is inserted and the two members 10 and 12 are brought together, with ribs 13 and 13a respectively contacting the bottom and top of core 11, there is a slight gap A between the opposing surfaces of the members 10 and 12, e.g. between shoulder 27 and ledge 28. This is done in order that the act of pressing the two members closely together will result in a crumbling of the frangible ribs in those portions thereof where the core 11 is in contact with any rib portion. In other words, the act of forcing the two members 10 and 12 together permanently deforms the ribs, thereby providing a recess in each such rib for receiving the core and for holding the tape-wound core member 11 tightly in place so that it cannot laterally shift within the space provided. Thus, in FIGURE 6A, it will be noted that a rib 13 is broken away wherever it lies opposite the upper edge of the tape-wound core member 11 but is not broken away at those portions 21 and 22 so that, in effect, each such rib 13 now is formed with a channel which is precisely dimensioned in accordance with the radial thickness of the tape-wound core member 11 so as to hold it without play or vibration in the corresponding casing half 10 or 12. Incidentally, it has been found that a tape-wound core 11 is especially effective in breaking off a portion of each of the frangible ribs 13 and 13a since each lamination acts as a cutting edge relative to the several ribs.

It will be appreciated that the concepts of this invention are in no way limited to the use of plastic casing members 10 and 12. Thus, if the material of which the members 10 and 12 are fabricated is of a type such as aluminum, which may render itself unsuitable for the production of upstanding knife-edged ribs which are of a deformable or frangible nature, it is readily possible to construct an insert for one of the members 10 or 12 in the manner shown in FIGURE 8. Such an insert 23 may be formed of a plastic or other suitable material having formed thereon a plurality of upstanding knife-edged ribs 24 which again are formed of a deformable or frangible material which may either take a permanent deformation upon application of a force thereto by the bottom surface

of the tape-wound core 10 or may be of a frangible nature such that the members 24 tend to crumble when force is applied thereto, again providing a cavity or recess in which a tape-wound core 11 may fit and be tightly held in place.

It is also possible to place one of the members 23 of FIGURE 8 in both the upper and lower casing members 10 and 12 prior to insertion of the tape-wound core 10 although this is ordinarily not necessary and may be undesirable since the use of a washer 23 as a separate element in place of the integral ribs shown, for example, in FIGURE 7, takes up additional space within the casing member. Thus, it is generally preferable to use only one such member 23 which is inserted into the member 10 immediately prior to the insertion of the tape-wound core member 11 into the annular recess in member 10 on top of the washer element 23.

FIGURE 9 illustrates an alternative embodiment of the invention which may be applied either to the construction of FIGURES 1-7 or may be applied to a separate washer element such as element 23 of FIGURE 8. In FIGURE 9, instead of employing radial knife-edged ribs to support the core, a plurality of concentric or spiral upstanding ridges are formed, but it is understood that the height and the angle of the ridges thus formed must be such that a permanent deformation or crumbling of the material will take place when the tape-wound core is inserted and pressure applied thereon in order that a cavity will be formed having the precise dimensions of the particular tape-wound core inserted so as to hold it tightly in place.

FIGURE 10 illustrates another alternative embodiment of the invention which may be applied either to the construction of FIGURES 1-7 or may also be applied to a separate washer element comparable to the washer element 23 of FIGURE 8. In FIGURE 10, the bottom surface 32, whether corresponding to the bottom surface 10a of element 10 or corresponding to the surface 23 of the washer-type element of FIGURE 8, is provided with a plurality of upstanding individual projections 26. Preferably, these projections extend around the circumference of the element and each is formed with a height and cross-section which permits it to be readily deformed or broken off at its topmost portion when pressure is exerted thereon by the core 11. Consequently, those projections 26 which are broken off or deformed provide a recess for receiving the core 11, whereas those projections which are not broken off provide means which are effective to exert forces against the sides of the core 11 to prevent its lateral shifting or vibration within the encasement.

It is to be further understood that the invention is in no way intended to be limited to the general type of construction shown in FIGURE 1 wherein two generally similar toroidal-shaped mating members, when fitted together, form the encasement for the magnetic core, but that the invention applies equally well to other known constructions including those wherein a magnetic core fits entirely within an annular trough-shaped member, with a generally flat lid or comparable sealing means providing the enclosure for the encasement. It will be readily understood by one skilled in the art and with reference to the disclosure herein, that the principles of this invention wherein a permanently deformable means is employed may equally well be used with other such constructions.

Having described a preferred embodiment of my invention and in addition several alternative embodiments, I desire it to be understood that various modifications and alterations may be made to the specific form shown without in any manner departing from the scope of my invention.

What I claim is:

1. An encased magnetic core comprising, a casing of non-magnetic material having walls forming a toroidal container which is generally U-shaped in radial section, a

toroidal magnetic core within said container with a clearance between the inner walls of said container and the outer walls of said magnetic core, means on the inner bottom wall of said U-shaped toroidal container supporting the bottom surface of said core, said supporting means being frangible so as to fracture readily under pressure and define a recess therein upon the application of pressure thereon by said core which recess substantially conforms to the shape of the contacting bottom surface of said core, said recess together with that portion of said supporting means which is not deformed by said core bottom prohibiting lateral movement of said core within said casing, and enclosure means for said casing tightly contacting the upper surface of said core to press said core tightly against said supporting means at the bottom of said toroidal chamber.

2. The invention as defined in claim 1 wherein said supporting means comprises at least three radially extending upstanding ridges integral with said inner bottom wall of said container; said ridges being knife-edged in cross-section with the narrow portion thereof extending upwardly toward the contacting surface of said core.

3. The invention as defined in claim 2 wherein each said ridge forms an acute angle of about 20° and extends approximately .02 of an inch above said inner bottom wall of said container.

4. The invention as defined in claim 1 wherein said supporting means comprises a separate washer-shaped element resting upon said inner bottom wall of said container, said separate element having a plurality of upstanding frangible elements on that face thereof which contacts said core bottom, said frangible elements readily fracturing to form said recess when said core is pressed tightly thereagainst.

5. The invention as defined in claim 1 wherein said supporting means comprises generally circular and substantially concentric upstanding knife-edged ridges integral with the bottom surface of said toroidal core-receiving chamber.

6. The invention as defined in claim 1 wherein said enclosure means also includes frangible means on its inner surface which contacts the upper surface of said core to thereby also form a recess therein substantially conforming to the contours of the upper surface of said core so as to aid in preventing lateral displacement of said core within said casing.

7. The invention as defined in claim 1 wherein said supporting means comprises a plurality of discrete pointed projections extending upwardly from said inner bottom wall of said toroidal chamber, whereby certain of said projections are permanently deformed by said core when said core is pressed tightly against said inner bottom wall, and the remainder thereof which are not so permanently deformed exert pressures on the sides of the said core to prohibit lateral displacement thereof within said casing.

8. In combination, a magnetic core, a casing for said magnetic core comprising, two separate mateable members, one of said members having an inner bottom wall and opposing inner side walls forming a chamber receiving said magnetic core with clearance between the inner side walls and the corresponding surfaces of the magnetic core, the other of said members having an inner top wall to oppose said inner bottom wall when said members are mated with spacing therebetween when said member are

65 fully mated which at least equals the corresponding dimension of said magnetic core, a plurality of upstanding frangible elements projecting outwardly from at least one of said inner top and bottom walls to form top and bottom core abutting surfaces whose spacing is less than the corresponding dimension of said core, whereby upon the exertion of force upon said mateable members forcing said members together into full mating position at least a portion of said upstanding frangible elements are permanently deformed to form a recess for the magnetic core

for preventing lateral motion of the magnetic core within
said casing.
